UNITED STATES PATENT OFFICE.

WILLIAM LYNES, OF SPARKHILL, ENGLAND.

APPLIANCE FOR USE WITH METALLURGICAL OR CHEMICAL VESSELS.

SPECIFICATION forming part of Letters Patent No. 728,122, dated May 12, 1903.

Application filed December 6, 1902. Serial No. 134,196. (No model.)

To all whom it may concern:

Be it known that I, WILLIAM LYNES, brass-founder, a subject of the King of Great Britain, residing at 557 Stratford road, Sparkhill,

5 near Birmingham, England, have invented certain new and useful Appliances for Use in Connection with Vessels Employed in Metallurgical, Chemical, and Analogous Operations, of which the following is a specification.

10 This invention has relation to accessory appliances to be used in connection with crucibles, melting and casting pots, and other vessels used in metallurgical, chemical, glass-working, and analogous operations in which

15 deleterious or obnoxious fumes dangerous to health or affecting the comfort of workmen and other operatives are evolved, such appliances consisting, primarily, of attachments for extracting or exhausting the said fumes

20 from the casting-pots or like vessels and carrying them away to a chimney, shaft, or other outlet before they can escape into the shop or apartment in which the operation is being conducted, such attachments being so ar-

25 ranged as not to interfere with the handling or manipulation of the vessels in pouring the molten metal and performing analogous operations, and in combination with them means are provided for facilitating the skimming of

30 the molten metal or other contents of the pot and inspecting the said molten metal or the like when the fume-extractor is in position.

Figure 1 of the accompanying drawings represents in elevation my fume-extraction 35 appliance and the accessories used in connection therewith, showing the same applied to an ordinary crucible such as is used in the melting and casting of brass in brass-foundries and in other analogous metallurgical

40 operations in which the molten metal contained in the pot evolves or is liable to evolve deleterious fumes on being removed from the melting-furnace and brought into contact with cold air. Fig. 2 is a vertical sec-

45 tion of the said pot and the appliances attached thereto. Fig. 3 represents a horizontal section of Fig. 2 upon the dotted line x, showing the body part of the fume-extractor in plan. Fig. 4 shows, upon a reduced scale,

50 the pot, with fume-extractor attached, in the act of being tilted for pouring the molten metal contained therein. Fig. 5 is a perspec-

tive view of a brass-foundry or like shop fitted with fume-extracting appliances and showing such appliances in use in connection with 55 brass-casting pots.

The same letters of reference indicate corresponding parts in the several figures of the drawings.

The appliance to be used in connection 60 with melting or casting pots in the manner represented for the purpose of exhausting, extracting, or abstracting and carrying off the fumes evolved from the molten metal when the pot is removed from the melting-furnace consists of a detachable and portable hood or bonnet a, made of iron or steel and covered, if necessary, with asbestos or like heat-resisting material (or the said hood may be made of fire-clay or other refractory ma-

65 terial) and adapted to be applied to the mouth of the pot or crucible. Leading from the crown or the back of the crown of the said hood is a neck or outlet b, which may either be made as a fixture to the hood, as in the ar- 70

angement shown, or may have a swiveling movement, or it may be made to constitute the socket part of a ball-and-socket joint, and to this said neck a flexible pipe or tube c or other flexible conductor to provide for carry- 75

80 off the abstracted fumes (but without interfering with the manipulation of the pot) is connected by a clamp or clip c' or by binding-wires or in any other convenient manner, or the socket may be made in suit- 85

ably-articulated sections or short tubular lengths, whereby it is made flexible. The flexible shaft or conductor is arranged to lead directly or indirectly into a stack, chimney, or other uptake, which may or may not be pro- 90

vided with a fan for inducing a draft, or it may be connected with an exhauster of any suitable type.

The fume abstracting or exhausting hood is adapted to be applied, as shown, to the 95 mouth of the crucible d or to the open top of a casting, melting, or mixing pot or other vessel used in metallurgical operations, and for this purpose the lower edge has a flange a', which rests on the top edge of the said pot 100 and is provided with a skirting or with a series of depending ears or clips a'', adapted to socket onto and embrace the walls of the upper part of the said pot, as clearly set forth

in Figs. 1 and 2. This flanged part of the hood when resting on the top edge of the pot also constitutes an abutment against which studs or projectings lugs h on the inner sides 5 of the arms, grips, or jaws of the crucible-tongs may come and take a bearing when the pot is laid hold of by the said tongs for transportation from the furnace to the mold or from one mold to another, and the jaws of the 10 said tongs may also be arranged to embrace and grip the hanging ears or clips. These means for holding down or retaining the hood in position over the mouth of the pot during the transportation of the pot or the pouring of 15 the molten metal are shown in Fig. 4, or instead of holding down the hood through the medium of the crucible-tongs in either of the manners as above described the skirting which hangs from the rest-flange of the hood 20 may be split or made flexible, so that it will either grip the mouth of the pot automatically or else admit of the skirting when gripped by the tongs being closed or gathered in around the outside walls of the pot and again 25 expanding, so as to be freed from the said pot when the grip of the tong-jaws is relieved. The material of the hood and skirting is cut away at the top and front, so as to leave a 30 gap or clearance at a^3 , corresponding when the hood is in position to the pouring-lip d' of the pot, and the gap thus made serves as a pouring and sight hole, which is more or less covered by a hinged lid or flap e , connected, preferably, by stiff hinge-joints e' to 35 the roof or crown of the said hood in such a manner that the said lid may be adjusted to and fixed at any angle or in any desired position relative to the sight-hole, so as to leave more or less clearance for viewing the metal 40 in the pot. This cover may be made of metal or of mica, wire-gauze, or other transparent or semitransparent refractory material, and when set at a certain angle relative to the gap it may also serve as a baffle or means for 45 deflecting or preventing the escape of flame or fumes from the inside of the pot and hood.

Before a pot containing molten brass or other metal is removed from the melting-furnace a temporary iron, plumbago, or like 50 cover is applied to the mouth thereof pending the application of the detachable fume-extractor thereto, and, if necessary, the said pot may be temporarily supported in a stand, frame, or cradle, which prevents the foot being pulled over by the swinging of the flexible pipe or fume-conveyer while the hood is 55 being applied to the mouth of the pot after the removal of the cover or stopper therefrom.

60 In connection with the fume-extraction attachment to the pot I propose to employ a detachable pan or vessel f , which is adapted to receive the skimmings or scum which is scraped from the surface of the metal prior 65 to pouring. This pan is adapted to be hung by hooks f' or otherwise from the edge of the pot or from the hood itself immediately in

front of the pouring-lip and also in front of the pouring and sight hole in the hood in such a manner that the mouth of the same comes 70 in the same level as or a little below the said pouring-lip of the pot. This pan or attachment forms a convenient removable receptacle for the scum or skimmings, which are removed by a rake or other tool from the surface of the molten metal prior to pouring, and it preferably has a concaved or curved inner side f^2 , which conforms to the contour of and seats against the front of the pot. Further, the open top is provided with an 80 overhanging metal shield g , preferably formed of wire-gauze or perforated metal, attached to one side or both sides and adapted to provide a means for deflecting the fumes arising from the skimmings back into the hood without interfering with the inspection of the 85 contents of the pot by the workmen during the skimming operation. The said shield is so formed or disposed as to leave a gap or opening at g' for the insertion of the skimming-tool.

The flexibility of the pipe or tube c admits of the ready transportation or manipulation of the attachment or exhauster in applying the latter to the pot or vessel and also permits the pot, with the attached hood, to be freely inclined or tilted for pouring out the molten metal or other contents of the pot and for other purposes, as may be necessary in the performance of casting or other operations. Further, by means of these flexible branch connections a number of hoods or exhausting-covers may be attached or coupled to single main outlet-pipe fixed or hung in any convenient manner and running into a 105 chimney or uptake-shaft, as shown in the perspective view Fig. 5, and thus the whole of the covers or exhausters in use in a shop or foundry may be connected to a common outlet.

A further advantage attendant on the use of the appliances herein described is that the fumes or vapors exhausted from the vessels in certain operations will be condensed and collected in the branch and main outlet-pipes, 115 from which they may be readily collected when sufficient quantities have accumulated, and in this manner commercially valuable substances—such, for instance, as practically pure oxid of zinc in the case of brass-founding—may be easily obtained and utilized as 120 desired.

The exhausting hood or cover and its accessories, as above described, may be adapted for use in connection with portable vessels used in various metallurgical operations other than melting and pouring and also in pouring, decanting, mixing, and otherwise dealing with acids, alkalies, and other chemicals from which poisonous, deleterious, and 125 other obnoxious fumes are evolved.

Having fully described my invention, what I desire to claim and secure by Letters Patent is—

1. An appliance for exhausting or extracting and carrying away fumes and vapors from crucibles or other vessels, consisting of a hood, cap or cover adapted to be applied to the mouth of the crucible and provided with an inspection and pouring gap and with an outlet, and means for connecting the outlet with a suitable offtake.
- 5 2. A portable appliance for exhausting or extracting and carrying away fumes or vapors from crucibles or the like, consisting of a hood, cap or cover having an inspection and pouring gap, means for holding the device upon the mouth of the vessel, an outlet projecting upward from the hood, and a flexible tube connecting the outlet with a suitable offtake.
- 10 3. A portable and detachable fume extracting or exhausting hood cap, or cover adapted to be applied to the mouth of the crucible or other vessel, a flexible conduit connecting the vessel with a suitable offtake and the hood or cover having a gap for inspecting or pouring the contents of the vessel, and a hinged or 15 adjustable lid or baffle disposed over the gap.
4. A portable and detachable fume extracting or exhausting hood, cap or cover for crucibles and the like, having a flange or skirting adapted to rest upon the edges of the mouth of the top of the vessel and having depending ears or clips to embrace the walls of the vessel and to present a means to be engaged by the implement employed in handling the crucible.
- 30 5. The combination with a fume-extractor 35 provided with an inspection-gap, of a detachable pan or receptacle for skimmings or the like, means carried by the pan for detachably connecting it with the crucible, and an open-work guard or screen disposed to admit 40 of the introduction of a tool or implement through the inspection-gap and into the interior of the hood.

In testimony whereof I have hereunto set my hand in presence of two subscribing witnesses.

WILLIAM LYNES.
